UNITED STATES PATENT OFFICE.

HENRY J. HARTIG, OF BROOKLYN, NEW YORK.

GAS-ENGINE.

SPECIFICATION forming part of Letters Patent No. 415,197, dated November 19, 1889.

Application filed July 26, 1889. Serial No. 318,658. (No model.)

To all whom it may concern:

- Be it known that I, HENRY J. HARTIG, of Brooklyn, county of Kings, and State of New York, have invented certain new and useful 5 Improvements in Gas-Engines, of which the following is a full, clear, and exact description, reference being had to the accompanying drawings, and to the letters of reference marked thereon.
- 10 My invention relates to engines wherein the explosive force of gas, or gas and air, is employed as the motive power, and which are commonly known as "gas-engines" or "gas-motors."
- 15 The object of my invention is to produce an engine of the class named which shall be of few and simple parts, powerful, reliable, and effective, compact and convenient in arrangement, economical of fuel, of which the 20 various working parts are easily accessible and removable, and which may be operated at high or low speed with equal certainty and efficiency.

To accomplish all of this and to secure other 25 and further advantages in the matters of construction, operation, and use my improvements involve certain new and useful arrangements or combinations of parts, peculiarities of construction, and principles of 30 operation, all of which will be herein first fully described, and then pointed out in the claims.

In the accompanying drawings, forming part of this specification, Figure 1 is a partial 35 elevation and section of my improved engine upon a plane at right angles to the main shaft. Fig. 2 is a front view, partly in section and partly in elevation. Fig. 3 is partial plan view of the base corresponding with Fig. 2 40 and showing the general location of the cylinders and valve-chamber. Fig. 4 is a horizontal sectional view of the valve-chamber detached. Fig. 5 is a sectional elevation at right angles to the main shaft, showing a 45 governor and connections with the check-valve in the valve-chamber. Fig. 6 is a side elevation showing the means and connections for operating the ignition-valve. Fig. 7 is a 50 sectional view enlarged beyond previous figures, showing the construction of the ignition-valve; and Fig. 8 is a top or plan view corresponding with Fig. 7. Fig. 9 is an ele-

vation of the plunger detached from the casing shown in Fig. 8.

In all these figures like letters of reference 55 wherever they occur indicate corresponding parts.

A is the main shaft of the engine, journaled in suitable standards B B, mounted upon a base or bed C. The shaft A carries a fly-wheel D, which may also be used as a belt-wheel, and is supplied at one portion with a disk E, driven by a connecting-rod F, leading from the main piston G, and at another point with a disk H, which drives the gas- 60 pump piston I through rod K.

L is the power-cylinder, within which the explosive force of the gas or fuel is utilized to drive the main piston G. M is the pump-cylinder, into which the fuel is drawn and 70 from which it is forced into the explosion-chamber. These two cylinders are arranged in line upon the bed-plate and firmly secured thereto. While the engine shown is of the variety known as "compression-engines," from the fact that the fuel is compressed before being exploded, it should be 75 distinctly understood that my improvements are not confined to compression-engines, but may be applied in others as well; and while 80 the general arrangements are chiefly applicable in upright engines the peculiar ignition-valve and the valve-chest are in no way 85 to be confined to use in either explosive or upright engines, but may be used in any style.

N is a chamber extending on one side a sufficient distance to establish communication between a port a, leading into the pump-cylinder, and a port b, leading into the main 90 cylinder L, and this chamber I call a "valve-chamber," because the valves all operate in or in connection with it. Within chamber N is an air and gas valve c, which as pump-piston I is retracted rises and admits gas 95 from any source through opening d and connecting-channels, and at the same time admits a quantity of air from the exterior through separate channels ee. This mixture constitutes the fuel which is to be exploded. 100 It enters the pump-cylinder and the valve-chamber. When piston I reaches its highest point, valve c closes, and upon descent of piston I the fuel is forced past the check-

valve *f* and into the chamber in which it is to be exploded, of which chamber the space beneath the main piston *G* is a port. The explosion is effected through an ignition-
5 valve applied upon the valve-chest. (Shown in position at Fig. 4 and in detail in Figs. 7 and 9.)

O represents the valve-casing, within which is a plunger *P*. This casing is removably applied upon the valve-chest and communicates with the interior thereof through an opening *g*. Gas from valve-chamber *N* enters at *g*, passes around plunger *P*, through channel *g'*, thence through an opening governed by a
15 needle-valve *g''*, thence into a recess *g''*, formed in the casing *O*. The plunger is recessed at top and fitted with a removable plug *Q*, (screw-threaded,) having a conical projection or portion *Q'*, above which projection the
20 plug *Q* is slightly tapered or reduced in diameter to afford a narrow recess *h* between the plug and the shell of the plunger, increasing in area from top to bottom, as plainly shown. In the region of channel *g''* the exterior of
25 the plunger is recessed, as at *i*, and perforated, as at *i'*. When the plunger is in proper position, a small quantity of the gas or fuel escapes from channel *g''* through perforations *i'*, through recess *h*, and out at opening or
30 mouth *k*, where it is ignited by a small flame maintained at a jet-orifice *l*, suitably located for the purpose. The movements of the plunger are so regulated or timed that when ignition takes place the plunger will uncover
35 mouth *g* and close mouth *k*, the ignition extending to the contents of the explosion-chamber. The chamber *h*, being of tapered form, is not liable to become clogged, and affords a free and abundant access of gas to
40 the region of the conical plug *Q'*, from whence it can easily escape to be ignited. As the plunger descends the channel *g'* and passages communicating therewith have abundant time to become charged with live gas ready
45 for the succeeding explosion, and the ignition is thus enabled to take place with certainty no matter at what speed the engine may be operated. The plunger may of course be made cylindrical or of any other figure, and,
50 while it is preferred to move it vertically, it may be moved in horizontal or other direction. It may be easily removed for cleaning, if necessary. It is moved by any suitable connection with the main shaft.
55 *P'* is a rod connected with the plunger and operated by a lever *P''*, one end of which engages with a cam-slot in disk *E*. Any other equivalent means may be substituted for these special devices. The check-valve *f* is raised
60 from its seat whenever the speed of the engine is increased beyond a desired degree, so that as the piston *G* descends the gas, which would otherwise be compressed beyond the degree due to the action of the pressure-
65 pump, finds an escape back past the check-valve, and what remains in the explosion-chamber at the instant of explosion, being of

less pressure than ordinarily, will produce a lighter effect upon the piston and allow the engine to gradually resume its proper speed. 70

To move the check-valve I connect it with a suitable governor, which may be of any preferred construction, but arranged to operate at the time desired. In the form shown weighted arms, as *R R* are hinged so as to 75 swing outward from the center more and more as the speed increases. They are connected with a sliding collar carrying a cam *m*, as by jointed rods *n*. A lever *o*, suitably located and hinged, is depressed by cam *m* 80 when the latter is carried along to the proper point, and by connecting rods *p p'* raises the check-valve at times and in a manner which will be readily understood.

Within the valve-chamber the check-valve 85 is screened by a wall or partition *q*, extending out toward the ignition-valve, the purpose of which is to insure a thorough ventilation of that portion of the explosion-chamber—that is, so that the incoming gas or fuel 90 shall drive out all the exploded material and prevent the accumulation of dead material in the region of the port leading to the ignition-valve.

The improved engine may be used for any 95 purpose.

At *S* is a water or other pump conveniently disposed on the base and driven from the main shaft by gears *T T* and suitable connections. Any other machine may be put 100 in the place of the pump.

V V are chambers through which a supply of water may be employed to prevent over-heating.

W is the exhaust-channel.

The valves are all accessible from the top, the parts are all simple and easy to make and mount, not liable to get out of order, and the engine has been found to admirably answer the purpose or object of the invention previously set forth. 105

Having now fully described my invention, what I claim as new herein, and desire to secure by Letters Patent, is—

1. In a gas-engine, the combination, with 115 the power-cylinder and pump-cylinder located and arranged substantially as shown, of a valve-chamber extending from one cylinder to the other and establishing communication between the two, said chamber sustaining a gas-valve covering the separate inlets for gas and air, a check-valve connected with and operated by a governor, and an ignition-valve, substantially as shown and described. 120

2. In a gas-engine, the combination, with the valve-chamber establishing communication between the power-cylinder and gas-pump, of a check-valve, a partition *g*, arranged to direct the flow of gas in the region 130 of the check-valve, a governor, and means for connecting the check-valve with the governor, substantially as and for the purposes set forth. 125

3. In combination with the check-valve located in the valve-chamber, a partition g , arranged to direct the flow of gas, substantially in the manner and for the purposes set forth.
- 5 4. The removable plug, combined with the plunger of an ignition-valve for gas-engines, said plug being gradually reduced in diameter, as explained, and forming with the shell of the plunger a gas-channel of gradually-
10 increasing area, substantially as shown and described.
5. The removable plug Q , combined with perforated plunger P and having a conical projection Q' , located and arranged substantially as shown and described.
- 15 6. The valve-casing O , having inlet and outlet g_1 , channel g' , and needle-valve g^2 , combined with a perforated plunger P , having removable plug Q Q' , substantially as shown and described. ²⁰

In testimony that I claim the foregoing I have hereunto set my hand in the presence of two witnesses.

HENRY J. HARTIG.
